United States Patent Office

Des. 203,124
Patented Dec. 7, 1965

203,124

CHILD'S WHEELED VEHICLE

Eugene E. Jackson, 1501 Overland Ave.,
Youngstown, Ohio

Filed Jan. 22, 1965, Ser. No. 83,531

Term of patent 7 years

(Cl. D34—15)

The figure is a perspective view of a child's wheeled vehicle, showing my new design; the opposite side is substantially similar to that shown.

I claim:

The ornamental design for a child's wheeled vehicle, as shown and described.
